UNITED STATES PATENT OFFICE.

REGINALD A. FESSENDEN, OF BROOKLINE, MASSACHUSETTS, ASSIGNOR TO SUBMARINE SIGNAL COMPANY, OF PORTLAND, MAINE, A CORPORATION OF MAINE.

METHOD AND APPARATUS FOR SIGNALING AND OTHERWISE UTILIZING RADIANT IMPULSES.

1,384,014.

Specification of Letters Patent.

Patented July 5, 1921.

Application filed January 14, 1918. Serial No. 211,758.

To all whom it may concern:

Be it known that I, REGINALD A. FESSENDEN, of Brookline, in the county of Norfolk and State of Massachusetts, a citizen of the United States, have invented new and useful Improvements in Methods and Apparatus for Signaling and Otherwise Utilizing Radiant Impulses, of which the following is the specification.

10 My invention relates to the production and utilization of radiant impulses both in the ether and in matter. For example, light waves, heat waves, ultra-violet waves, X rays, Hertzian waves, sound waves, and the like. It relates more especially to signaling and detecting objects by radiant impulses and has for its object increased efficiency in the utilization of radiant impulses and more particularly increased efficiency in signaling 15 and detecting bodies by means of radiant impulses.

Figures 1 to 7 show, partly diagrammatically, apparatus adapted for carrying out my invention.

25 In Fig. 1, 14 is a reflector for radiant impulses constructed in any suitable way so as to reflect, in the direction from which they came, radiant impulses striking it, no matter, within certain limits, how the reflector may be tilted.

For example, in Fig. 4 the radiant impulses from the lamp 22 on striking the reflector 14 are reflected toward the direction of the lamp, as shown in the dotted lines.

35 I accomplish this by arranging three reflecting surfaces 11, 12, and 13 so that each is at right angles to the other two. From this construction I obtain the result that no matter how the reflector is tilted, so long 40 as the radiant impulses enter the solid angle formed by the three reflecting surfaces 11, 12, and 13, the light or other radiant impulse is reflected back toward the source.

The optical properties of such geometrical 45 arrangement of plane reflecting surfaces are easily established from long known optical laws but so far as can be ascertained have never been practically constructed or utilized, and in the absence of any name for 50 this arrangement of three reflecting plane surfaces at right angles to each other it has

been called, as a matter of convenience, the reflector.

The linear dimensions of these reflecting surfaces are preferably large multiples of 55 the wave length of the radiant impulses used.

These reflecting surfaces 11, 12, 13 may consist of three mirrors, as shown in front view in Fig. 1 and in side view in Fig. 2. 60 For signaling purposes they are preferably mounted as shown with a diagonal of one reflecting surface 11 horizontal, though the exact arrangement is usually a matter of no importance.

65 The reflector 14, formed of the three reflecting surfaces 11, 12, 13 is conveniently attached to a rod 15. To this rod 15 is attached a shutter 16, as shown, operated in any convenient manner—for example, by a 70 key or a photographic bulb release or, as shown, by the string 45. 17 is a mirror attached to the sleeve 18 so that it can be slid up and down the rod 15. When the mirror 17 is at an angle of approximately 45°, it 75 and the upper reflecting surface 11 form a trench periscope so that an eye placed, as shown, at 46, Fig. 2, will see by reflection objects to the right as shown by the dotted lines. The shutter 16 is omitted in Fig. 2 80 in order to show more clearly the use of the apparatus as a trench periscope for signaling.

Fig. 3 shows another form of reflector in which instead of using three plane mirrors 85 a tetrahedron consisting of the corner of a cube of transparent material such as glass is used, 11, 12, and 13 being the portions of the sides of the cubes which meet together at one corner and these sides of the cube being silvered while the fourth side of the tetrahedron, facing the observer, as shown in Fig. 3, is left unsilvered. The silver coating is covered with some protecting material, such as cement, rubber, or metal. 95

The corner where the three sides 11, 12, 13 meet is preferably ground off parallel to the face of the glass tetrahedron opposite to the silvered sides 11, 12, 13.

From monochromatic light this form of 100 reflector behaves exactly the same as the three mirror type but has several advantages.

For example, it is more compact and the sides being once ground at the right angles the reflecting surfaces always maintain their true relation. Also there is some advantage when non-chromatic light is used in that the color of the reflected light gives some indication of the way in which the reflector is held and somewhat widens the field.

10 The object of grinding off the corner 20 as shown in Fig. 3 and polishing it, or in the case of the three mirror type drilling the hole 20', as shown in Fig. 4, is so that the observer by placing his eye in the position 15 46' may observe the signaling light 22.

Fig. 4 shows an arrangement of apparatus suitable for communicating between the first line trenches and the rear trenches or between the advance and the first line trenches.

20 During the present year, 1917, the official reports of the operations on the west front are to the effect that the best method of signaling so far found for the advance is the signaling lamp, substantially a heliograph 25 using artificial instead of solar illumination. The objections to this, as stated in the official report, are that when provided with sufficient storage battery to last in case the advance is cut off by barrage it is too heavy; 30 also that the man carrying it cannot carry his rifle or anything else; also that there is often considerable difficulty in the advance signaler and rear signaler getting in touch with each other, since both projecting lamps 35 have to be aligned simultaneously.

The present invention overcomes these difficulties and has other advantages.

The method of using is shown in Fig. 4. Here 21 is a shutter, 22 a source of light, 23 40 a reflector, 24 a telescope. These are used by the signaler to the rear, or in the case of advance by the signaler in the trenches. 14 is the reflector, 16 a shutter, 20' a hole bored at the corner of the reflecting planes, and 46' 45 is the eye of the forward signaler. The reflector is all that is carried by the forward signaler who, in an advance, may be four or five miles in front of the trenches where the rear observer is.

50 The operation is as follows: The front signaler goes forward equipped with the reflector 14, and, as this weighs less than eight ounces, carrying his full equipment of rifle, etc. Suppose when he is a couple of miles in advance it is desired to communicate with him. To do this the rear signaler swings his projecting lamp 22, 23 over the terrain, keeping his eye at the telescope 24. As soon as the beam of the projecting lamp strikes the reflector 14 the rear observer sees a flash and knows that the projecting beam is in the right direction. At the same time the forward signaler with his eye at the point 46' sees the flash from the projecting lamp. The 55 rear signaler then by moving the shutter 21

signals the call letter of the forward signaler several times and then leaves the shutter 21 in the open position. The forward signaler then moves the shutter 16 and cuts off the beam of light reflected back to 24, 70 and thus signals to the rear observer and communication is thus established.

In signaling at night time where it is not desired that the beam of the projecting lamp 22, 23 should be seen by the enemy, in place 75 of a tungsten lamp 22 a source of ultra-violet radiation, such as a quartz mercury tube, may be used with a screen cutting off all visible radiation, as is well known in the art, and the round corner 20 or the opposite 80 face of the tetrahedron may be coated with a fluorescent substance, such as sulfate of quinin, and also the object glass of the telescope 24.

This method has the following advantages 85 for signaling during an advance:

(1) The whole apparatus carried by the advance signaler weighs less than eight ounces and consequently he can carry his usual equipment.

(2) The apparatus cannot get out of order.

(3) It can be operated isolated from all supplies for any length of time as it does not require fresh batteries, lamps, etc., to be 95 brought up from the rear through territory exposed to shell fire.

(4) The signaling range may be much greater than with projection lamps, as the only light source is operated from a fixed 100 position and may be an arc lamp projector of a hundred times the power of a projection lamp.

(5) No time is lost in establishing communication, as instead of two projectors having to be lined up communication is established at once as soon as the rear projector is swung in such direction as to point to the advance signaler.

(6) As the direction of reflection back is 110 not influenced by the wabbling of the reflector, the forward signaler does not have to stop in order to receive messages from the rear signaler, and in fact by facing the reflector toward the rear and using the periscope mirror as shown in Figs. 1 and 2, he 115 may receive and transmit messages while walking or even while running forward.

(7) The forward signaler can operate his apparatus while protected in the trench by 120 sticking the pointed end 19 of the bar 15, Fig. 1, in the ground so that only the reflector, a few inches square, projects above the trench.

(8) It is easily manufactured and inexpensive.

For the above reasons, and others, it is extremely well adapted for signaling during an advance and for other work, such as signaling between an artillery station and an 130

aeroplane and where ultra-violet light or infra-red light is used it has the additional advantage over wireless and other forms of signaling that the fact that signaling is going on is not disclosed to the enemy.

Applicant has discovered that infra-red radiation is especially advantageous in that it is not affected by transmission through fog or smoke to anything like the same extent to which ultra-violet radiation is affected.

Fig. 5 shows the application of the invention to marine work—in the case shown to a buoy marking the position of a channel.

Here 25 is the buoy having a number of these reflecting prisms 14, 14, 14, 14 of any kind of colored glass desired arranged as a crown on the top of the buoy.

A ship desiring to pick up the channel, on coming within three or four miles of the supposed entrance to the channel, swings its projector around the horizon. Immediately the projector beam is pointing in the direction of the buoy the man standing beside the projector sees the answering flash, since no matter how the buoy 25 is rocking or tilting on the water the beam is always reflected toward the source, *i. e.*, toward the projector.

This method has the following advantages:

(1) The buoy may be picked up over a greater distance than a light buoy because the source of light *i. e.*, the arc lamp projector, of the ship is a much more powerful source than the source of light installed on the light buoy.

(2) The buoy cannot be mistaken for shore lights or any light carrying object.

(3) In time of war channels may be left marked with this type of buoy because the only way in which an enemy's ship could pick up the buoy would be by using this projector, in which case the enemy's ship would be immediately observed.

(4) A ship picking up a buoy in this way does not disclose the position of the buoy to any other ship in the vicinity as the reflected beam is sent back directly to the ship carrying the projector.

(5) Large and expensive buoys are not necessary as the apparatus will work just as well when installed on an inexpensive spar buoy.

(6) The cost of maintenance is practically nothing and there is nothing to get out of order as the prism crown can be protected by an iron grating.

Fig. 6 shows the apparatus applied to wireless telegraphy. In this case only one set of sending apparatus is necessary, as shown in the upper part of Fig. 6.

Here 26, 27 are the radiating conductors, preferably dimensioned so as to radiate Hertzian waves of a few centimeters wave length. 28 is an oscillating audion, or pliotron, pro-

ducing waves of a few centimeters wave length. 34 is a switch for signaling and 29 a source of electric power for exciting the audion 28.

The receiving apparatus is shown in the lower part of Fig. 6, where 30, 31 are the receiving conductors, 32 a wireless receiving apparatus of any suitable form, and 33 a double head telephone receiver.

14 is the reflector and 16 a shutter, in the present case preferably made of metal and slanted at an angle so that its plane is not perpendicular to the dotted lines showing the path of the Hertzian waves.

The operation is similar to that of the optical apparatus shown in Fig. 4.

Fig. 7 shows the apparatus arranged to operate with sound impulses of very short wave length.

The transmitting apparatus is shown in the upper part of Fig. 7 and consists of a source of high frequency oscillations 35, which may be a pliotron generator or, as shown, a high frequency dynamo giving say 50,000 cycles per second, of the type described in applicant's U. S. Patent 706,737, issued August 12, 1902.

36 is a transmitter to be used when the apparatus is used for telephoning. 37 is a key, kept closed when telephoning and operated when the apparatus is used for telegraphing. 39 is the source of sound, which may be an oscillator of the type shown in applicant's U. S. Patent 1,167,366, issued January 4, 1916, which has been found very suitable for producing such high frequency mechanical vibrations, or a condenser of the type shown in applicant's U. S. Patent 1,182,843, issued May 9, 1916, Fig. 5, with the additional improvement, *i. e.* the local battery 38, the addition of this local battery having been found to increase the efficiency of the apparatus as a generator. 40 is a diaphragm, which may be one plate of the condenser 29 or may be a separate plate of metal or other suitable material. The receiving apparatus is shown at the bottom of Fig. 7, where 42 is any suitable receiving apparatus, for example the oscillator above referred to, and 41 being either a plate of the condenser or a separate diaphragm. 44 is the receiver, which may be of any suitable type capable of receiving high frequency electrical vibrations, and 43 is a local battery. 14 is the reflector and 16 is a shutter, as above.

The method of operation is as described with reference to Fig. 4.

These ultra-audible sound vibrations, called by the writer "anacysms," have a number of advantages in that they can be projected as a well defined beam of sound and can be used for secret sending and operated by the heterodyne or similar apparatus.

While I have in the above specification described some of the uses to which my invention may be applied, I do not confine myself to those described as it will be obvious to those skilled in the art that it may be used in other ways.

What I claim is:

Means for signaling by radiant impulses

comprising a tetrahedron having three adjoining faces at right angles to each other 10 and a surface in proximity to said tetrahedron whereby the incidence of radiant energy on said tetrahedron may be determined.

REGINALD A. FESSENDEN.
